W. C. & J. Shenkel Atty.

UNITED STATES PATENT OFFICE.

JACOB SHENKEL, OF EAST LIVERPOOL, OHIO.

DESIGN FOR AN EARTHENWARE TEA-POT.

SPECIFICATION forming part of Design No. 12,961, dated June 6, 1882.

Application filed April 10, 1882. Term of patent 3½ years.

To all whom it may concern:

Be it known that I, JACOB SHENKEL, of the town of East Liverpool, in the county of Columbiana and State of Ohio, have invented and produced a new and original Design for Earthenware Tea-Pots, of which the following is a specification, reference being had to the accompanying drawings, forming part thereof.

Figure 1 is a sectional view of this newly-designed tea-pot. Fig. 2 is a side elevation of same.

My design consists in the globular form of the body of the pot, having on its surface the representation or imitation of a woven basket-covering impressed into the material of which the pot is made, and the form and style of the handle and spout.

A is the body of the pot, which is molded

of clay, in the form of a globe with flattened bottom, and a suitable opening at the top for the reception of a lid, B. The outside surface of both the body and lid is molded, stamped, or impressed with a design in imitation of a willow basket woven covering, and the handle and spout in imitation of cane stems. 25

The above-described design is intended to be applied to pottery-ware tea-pots made of clay, either in white, yellow, or brown ware.

Having described this invention, I claim—

The design for a tea and coffee pot, substantially as shown. 30

JACOB SHENKEL.
